US00D696125S

(12) **United States Design Patent**
Ring et al.

(10) **Patent No.:** US D696,125 S
(45) **Date of Patent:** ** Dec. 24, 2013

(54) **BOTTLE**

(76) Inventors: **Thomas J. Ring**, Palos Heights, IL (US);
John S. Letchinger, Wilmette, IL (US);
Daniel L. O'Malley, Wilmette, IL (US);
Kenneth W. Reick, Glen Ellyn, IL (US);
Linc E. Cholke, Vernon Hills, IL (US);
Kevin J. Cox, Northbrook, IL (US)

(**) Term: **14 Years**

(21) Appl. No.: **29/424,646**

(22) Filed: **Jun. 14, 2012**

Related U.S. Application Data

(60) Continuation of application No. 29/405,724, filed on Nov. 4, 2011, now Pat. No. Des. 664,856, which is a continuation of application No. 29/387,755, filed on Mar. 17, 2011, now Pat. No. Des. 653,546, which is a division of application No. 29/357,290, filed on Mar. 10, 2010, now abandoned.

(57) **CLAIM**

We claim the ornamental design for a bottle, as shown and described.

DESCRIPTION

FIG. 1 is a top perspective view of a bottle;
FIG. 2 is a front view of the bottle of FIG. 1;
FIG. 3 is a rear view of the bottle of FIG. 1;
FIG. 4 is a right side elevation view of the bottle of FIG. 1;
FIG. 5 is a left side elevation view of the bottle of FIG. 1;
FIG. 6 is a top view of the bottle of FIG. 1; and,
FIG. 7 is a bottom view of the bottle of FIG. 1.
The broken lines in the drawings illustrate the portions of the design that form no part of the claim.

1 Claim, 4 Drawing Sheets
